CLOSED FACE SPINNING REEL

R. Dell Hull, 6101 E. Apache St.,
Tulsa, Okla. 74101

Filed Nov. 17, 1972, Ser. No. 307,359

Term of patent 14 years

Int. Cl. D22—05

U.S. Cl. D22—25

Fig. 1

Fig. 2

Fig. 3

FIGS. 1 and 2 are opposite side elevational views of a closed face spinning reel embodying my new design;

FIG. 3 is a front end elevational view of the reel of FIG. 1;

FIG. 4 is a top plan view of the reel of FIG. 1;

FIG. 5 is a bottom plan view of the reel of FIG. 1; and

FIG. 6 is a rear end elevational view of the reel of FIG. 1.

I claim:

The ornamental design for a closed face spinning reel, substantially as shown.
